CLAIM

The ornamental design for an odor-removing apparatus for inclusion in a toilet, as shown and described.

DESCRIPTION

FIG. 1 is an isometric view from the upper right front of an odor-removing apparatus for inclusion in a toilet, including my new design;

FIG. 2 is a front elevational view thereof;

FIG. 3 is a rear elevational view thereof;

FIG. 4 is a right side elevational view thereof;

FIG. 5 is a top plan view thereof;

FIG. 6 is a left side elevational view thereof; and,

FIG. 7 is a bottom plan view thereof.
